DESIGN FOR A PORTABLE LAMP

Rudolf Popp, Valparaiso, Ind., assignor to McGill
Manufacturing Company, Valparaiso, Ind., a corporation of Indiana

Application November 8, 1943, Serial No. 111,625

Term of patent 7 years

To all whom it may concern:

Be it known that I, Rudolf Popp, residing at Valparaiso, in the county of Porter and State of Indiana, have invented a new, original, and ornamental Design for a Portable Lamp, of which the following is a specification, reference being had to the accompanying drawing, forming part thereof, in which;

Fig. 1 is a side perspective view of a portable lamp showing my new design; and

Fig. 2 is a bottom plan view thereof.

The characteristic features of my new design are shown in solid lines in the drawing.

I claim:

The ornamental design for a portable lamp, substantially as shown and described.

RUDOLF POPP.
